[57] **ABSTRACT**

This application discloses a can end having a scored tear-out panel and an integral rivet securing a pull tab to said panel, wherein the tear-out panel may provide for removal of substantially the full end panel. In order to prevent failure of the rivet during the initial opening process while at the same time not increasing the effort required to open the tear-out panel, beads are provided, one on each side of the rivet, in an outwardly facing Vee configuration. Each Vee may be composed of two separate beads or the Vee may be a continuous bead. The application gives the necessary parameters to achieve the desired results.

EASY-OPEN CAN END**BRIEF SUMMARY OF THE INVENTION**

This application is a continuation-in-part of an application, Ser. No. 241,535 filed Apr. 6, 1972, now abandoned.

The invention relates to the solution of a problem which was sought to be solved by a copending application in the name of Elton G. Kaminski, Ser. No. 113,330 filed Feb. 8, 1971, and in the parent application of the present invention.

It was pointed out in said copending applications that easy-open ends for cans have come generally into widespread use, particularly when solid foods are packed in cans, substantially the full end panel must be removed. Examples of foods which are packed in cans of this nature are things such as peanuts, potato sticks, candy, ground coffee, and the like.

Many of these materials now packaged in easy-open cans are packaged under high vacuum or high pressure; and in order to avoid danger of either explosion or implosion of the can end, the scoring residual is made relatively high. The presence of a heavier residual in the score places a greater strain on the rivet head during the opening process and particularly during initial portion of the opening process. In the opening of such an easy-open can, the pull tab is first lifted, thereby puncturing the can end, bending a portion of the end downwardly into the can. Thereafter, the panel with the score line is pulled upwardly by means of the pull tab to remove the panel from the can. During the initial lifting of the tab and bending down of a portion of the end, the rivet is subjected to substantial stress and it is at this point that failure most often takes place.

As was also pointed out in said copending applications, various procedures have been adopted in the past to try to overcome the problem of rivet failure. Some of these involve lancing of the tab or scoring behind the rivet; but these attempts have not been uniformly successful because of the wide range of products which are packaged in easy-open containers.

The parent application sought to solve the problem by means of a pair of beads, one on each side of the rivet, but at that time the parameters which are necessary in order to both prevent rivet failure and not unduly to increase the effort required to open the can were not known.

The objects of the present invention, therefore, are substantially the same as those of the copending applications, i.e. to provide a beverage type or a full panel easy-open can end in which the strain on the rivet during the opening operation and particularly during the first phase thereof is relieved so as to preclude rivet failure. At the same time, it is an object to accomplish prevention of rivet failure while at the same time not unduly increasing the effort necessary to open the can.

BRIEF DESCRIPTION OF THE DRAWINGS

FIG. 1 is a perspective view of a can end showing rivet failure.

FIG. 2 is a view similar to FIG. 1 showing a proper opening without rivet failure.

FIG. 3 is a plan view of a can end showing the beads which accomplish the object of the invention.

FIG. 4 is a view similar to FIG. 4 showing a modification; and

FIG. 5 is a diagram showing the parameters necessary in order to achieve the desired results.

DETAILED DESCRIPTION

FIG. 1 demonstrates what happens with conventional construction. It shows the underside of a panel of conventional form which has been torn from a can by means of a pull tab 19. At 20 it will be observed that the rivet has ruptured. When this happens, it is often impossible properly to remove the easy-open panel from the can.

FIG. 2 shows a similar view of a can end according to the present invention which has been opened and the underside of the removed panel 21 is shown in this Figure. It will be observed that the rivet has not been broken and thus a part of the object of the invention has been achieved.

In FIG. 3 a can end is indicated generally at 10. It is provided with a circular score line 11 defining the panel which is removed when the pull tab is actuated. The rivet which secures the pull tab to the top side of the can is indicated at 12. At 13 are indicated parallel beads. These beads are preferably depressed, but they will function equally well if raised. These beads are parallel to a diameter of the can end through its center 14, the diameter being indicated by the broken line 15. The broken line 16 indicates a tangent to the rear side of the rivet, i.e. the side of the rivet toward the center of the can end, which tangent is normal to the diameter 15.

Additional beads are indicated at 23 and these beads are generally parallel to the score line 11 so that they make a Vee configuration with the respective beads 13.

As shown in a modification in FIG. 4, the beads may be joined together in a continuous Vee or J-shaped bead as indicated at 33.

FIG. 5 is a diagram showing the relationship of the beads 13 to the rivet 12. The dimension A should be equal to about the rivet diameter plus one-sixteenth inch and the beads 13 should be equally spaced on either side of the rivet 12. They are of course parallel to the line 15 mentioned above.

The dimension B should be not less than 40 percent nor more than 50 percent of the rivet diameter. In other words, the beads 13 should not extend upward as shown in FIG. 6 beyond a tangent to the rivet 12 perpendicular to the line 15.

The dimension C should be not less than 73 percent nor more than 83 percent of the rivet diameter. If beads extend less than 73 percent toward the center of the can, insufficient stress is removed from the rivet and rivet failure is likely to happen. On the other hand, if the beads extend more than 83 percent (dimension C), the opening effort is increased to the point that it is unsatisfactory.

The beads 23 and the portions 23a of the beads 33 act as stiffeners on each side of the tab. Thus, when the end is initially opened, these stiffening beads cause more of the panel to fold downward toward the inside of the can. In other words, a greater arc length of score line to each side of the tab nose is initially fractured. This causes a fold line to assume a more normal position with respect to the ends of the beads which are closest to the center of the end.

It will be clear that minor modifications may be made without departing from the spirit of the invention. No limitation not specifically set forth in the claims is

therefore intended and no such limitation should be implied.

The embodiments of the invention in which an exclusive property or privilege is claimed are defined as follows:

1. In an easy-open metal can end having an integral rivet, a pull tab secured to said panel by means of said rivet, said panel being defined by a score line having a relatively high residual; a first pair of beads disposed equidistantly, one on each side of said rivet, substantially parallel to each other and to a diameter of said can passing through said rivet, and a second pair of beads generally parallel to the periphery of said can end, one of said second pair of beads being associated with each of said first pair of beads in a Vee configuration with the apex of said Vee configuration pointing toward the periphery of the can end.

2. The structure of claim 1, wherein the distance between said first pair of beads is equal to about the rivet diameter plus one-sixteenth inch.

3. The structure of claim 1, wherein each of said first

pair of beads extends forwardly of the rivet center between about forty percent and about fifty percent of the rivet diameter.

4. The structure of claim 1, wherein each of said first pair of rivets extends rearwardly of the rivet center between about seventy-three percent and about eighty-three percent of the rivet diameter.

5. The structure of claim 1, wherein the beads forming each of said Vee configurations are connected so as 10 to be continuous.

6. The structure of claim 1, wherein the distance between said first pair of beads is equal to about the rivet diameter plus one-sixteenth inch, each of said first pair of beads extending forwardly of the rivet center between about 40 percent and about 50 percent of the rivet diameter, and rearwardly thereof between about 73 percent and about 83 percent of the rivet diameter.

15 7. The structure of claim 6, wherein the beads forming each of said Vee configurations are connected so as 20 to be continuous.
